[57] CLAIM

The ornamental design for a portable handset telephone or similar article, as shown and described.

DESCRIPTION

FIG. 1 is a front, top and right side perspective view of a portable article showing our new design;

FIG. 2 is a rear elevational view thereof;

FIG. 3 is a bottom plan view thereof; and,

FIG. 4 is a right side elevational view thereof, the side opposite being similarly a mirror image.

The broken line showing of an antenna in FIGS. 1, 2 and 4 is for illustrative purposes only and forms no part of the claimed design.

FIG. 1

FIG. 2

FIG. 3

FIG. 4
